UNITED STATES PATENT OFFICE.

ROBERT H. WARREN, OF NEWARK, NEW JERSEY.

DESIGN FOR A STAIR-CARPET BUTTON.

SPECIFICATION forming part of Design No. 22,382, dated May 2, 1893.

Application filed March 8, 1893. Serial No. 465,178. Term of patent 7 years.

To all whom it may concern:

Be it known that I, ROBERT H. WARREN, a citizen of the United States, residing at Newark, in the county of Essex and State of New Jersey, have invented and produced a new and original Design for Stair-Carpet Buttons; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 is a front elevation of a stair carpet button showing my design and Fig. 2 is a central section of the same.

The leading feature of the design consists in a stair carpet button which is ornamented 20 at the center by a daisy-like figure, at the op-

posite ends by pointed ornaments and at the upper and lower edges by series of scallops.

In the drawings, *a* indicates an ornament resembling a daisy or similar flower of the composite order.

²⁵ *b, b*, are the outwardly pointed ornaments resembling in some degree the ornaments found on spear heads or flag staffs, and *c, c*, are the scalloped upper and lower edges which form convex outlines.

³⁰ What I claim as new is—

The design for a stair carpet button substantially as shown and described.

In testimony that I claim the foregoing I have hereunto set my hand this 7th day of ³⁵ February, 1893.

ROBERT H. WARREN.
